Attorney

UNITED STATES PATENT OFFICE.

HARRY MORRIS, OF GROVELAND, NEW YORK.

SNOW-PLOW.

1,272,839.

Specification of Letters Patent. Patented July 16, 1918.

Application filed March 13, 1918. Serial No. 222,109.

To all whom it may concern:

Be it known that I, HARRY MORRIS, a Russian subject, residing at Groveland, in the county of Livingston and State of New York, have invented certain new and useful Improvements in Snow-Plows, of which the following is a specification.

This invention relates to snow plows or snow road machines; and it consists in the novel construction and combination of the parts hereinafter fully described and claimed whereby the snow is removed from country roads by means of a plow attached to the front end of any approved make of automobile or motor car.

In the drawings, Figure 1 is a side view of the front end portion of a motor car provided with a snow plow according to this invention. Fig. 2 is a plan view of the plow from below.

The frame 2 of the motor car is of any approved construction, and 3 is its front axle provided with steering wheels 4 in the usual way. The frame is supported from the front axle by any approved form of springs 5.

The shape of the snow plow may be varied, but it consists essentially of two curved plates 6 secured together at their front ends which form a cutting edge 7 which is arranged in front of the middle part of the car. The plates 6 extend rearwardly and outwardly from the cutting edge 7, and their curvature and outline is made so that they cut through the snow on the road, and turn it over and pile it up on each side of the car clear of the car wheels. A horizontal lip or blade 8 projects forwardly from the bottom edge of each plate 6 and aids in removing the snow.

The curved plow plates are pivotally supported from the front axle 3 by means of a center brace 9, and two side braces 10. The center brace 9 is secured to the upper part of the plates 6 by forked arms 12, and 14 is an extension or branch of the center brace which is secured to the lower parts of the plates 6 by forked arms 15. The shape and connection of this center brace may be varied in many ways in carrying out this invention. The side braces 10 are pivotally connected with the axle; and at points between the road wheels and the sup-

porting springs, and their front end portions are connected to the middle parts of 55 the plow plates 6, stiffening ribs 17 being preferably provided at their points of junction with the plow plat.

A crossbar 18 is secured to the frame to the rear of the steering rod wheels, and if 60 desirable it may be slightly resilient. Rear braces 19 are pivoted to this crossbar 18, and their front ends are connected to stiffening ribs 20 on the rear parts of the plow plates.

Runners 22 are secured under the plow 65 plates at suitable places, and preferably on each side of the plow point. These runners run on the ground, and hold the plow a little above its surface. This snow plow is used to prevent the accumulation of snow on 70 country roads where it ordinarily hinders the travel of motor cars and other vehicles.

What I claim is:

1. The combination, with a motor car, of a snow plow formed of diverging plates 75 which form a cutting edge in front of the car, said plates being arranged to straddle and extend rearwardly beyond the front ground wheels and axle of the car, means for supporting the front parts of the plow 80 plates from the ground, front braces secured to the plow plates and pivoted to the said axle, and rear braces pivotally connected at their front ends with the plow plates and having their rear ends pivotally connected 85 with the frame of the car.

2. The combination, with a motor car, of a snow plow formed of diverging plates which form a cutting edge in front of the car, said plates being arranged to straddle 90 and extend rearwardly beyond the front ground wheels and axle of the car, means for supporting the front parts of the plow plates from the ground, a center front brace secured to the plow plates and pivoted to 95 the middle part of the said axle, side front braces also secured to the plow plates and pivoted to the end portions of the said axle, and rear braces pivotally connected at their front ends with the plow plates and having 100 their rear ends pivotally connected with the frame of the car.

In testimony whereof I have affixed my signature.

HARRY MORRIS.
